UNITED STATES PATENT OFFICE.

WILLIAM F. PATTEN, OF WASHINGTON, DISTRICT OF COLUMBIA.

TOILET NOVELTY.

Application filed February 1, 1926. Serial No. 85,274.

This invention relates to certain improvements in toilet novelties; and the nature and objects of the invention will be readily recognized and understood by those skilled in the arts involved in the light of the following explanation and detailed description of the accompanying drawings illustrating what I at present consider to be the preferred embodiments or mechanical expressions of my invention from among various other forms, arrangements, combinations and constructions of which the invention is capable within the spirit and scope thereof.

15 More specifically, the present invention is primarily directed to the provision of a toilet novelty or accessory for use in deodorizing the breath, although the invention is not restricted or limited to this particular use, as 20 the use thereof for medicating and treating diseases or ailments of the mouth, throat and nose, is contemplated by and included in the invention.

Those afflicted with the various forms of 25 halitosis, or bad or objectionable breath odors, whatever the cause may be and whether of a permanent or temporary character, are loath to employ in public the various forms of deodorants, which themselves 30 generally afford but temporary relief and must be constantly used at short intervals to overcome the objectionable breath odors. The repeated public use of such deodorants merely serves to direct attention to the application, and their use is particularly objectionable to women in public and at social 35 affairs where the necessity of removing bad breath odors is at a maximum.

Therefor, one of the main and fundamental objects of this invention is to provide 40 a breath deodorizing toilet novelty or accessory which is readily portable and carried upon the person, and of a form and design to imitate or simulate and appear to 45 an observer as, an article generally carried upon the person and employed for another purpose, and which can be inserted in or touched by the mouth to apply a deodorant to the breath, in a plausible manner as the 50 natural use of the article.

Another object of the invention is to provide 55 a breath deodorizing toilet novelty or accessory in which a supply of deodorant in liquid form can be contained and fed therefrom by capillary attraction solely, so that

the deodorizer can be carried upon the person in any position without discharge of the liquid deodorant and resulting soiling of objects with which the same comes in contact, but in which a sufficient quantity is instantaneously supplied to the mouth upon contact therewith or insertion therein, to deodorize the breath.

A further object of the invention is to provide a design and construction of breath deodorizing toilet novelty or accessory for carrying on the person, in which a reservoir for liquid deodorant is formed to contain a sufficient supply for use over a considerable period of time and capable of being readily 70 filled with deodorant, and in which the deodorant is fed through a channel by capillary attraction to an exposed point for engagement by the mouth to supply a small quantity thereto for deodorizing the breath. 75

80 A further object of the invention is to provide a design and construction of breath deodorizing toilet novelty having the foregoing desired general characteristics, which lends itself readily to manufacture in quantity from various materials in artistic and attractive forms and designs.

With the foregoing and certain other objects and results in view, which other objects and results will be readily recognized 85 by those skilled in the art from the following description the invention consists in certain novel features in constructions and in combinations and arrangements of elements, as will be more fully and particularly referred 90 to and specified hereinafter.

95 Referring to the accompanying drawings, in which similar reference characters refer to corresponding parts throughout the several figures thereof:

Fig. 1, is a view in side elevation of one form of the invention simulating a cigarette holder.

Fig. 2, is a longitudinal section through the device of Fig. 1, showing the reservoir 100 and capillary feeding duct and feeding member therein.

Fig. 3, is a side elevation of another form of the invention in which the filler plug for the deodorant reservoir is formed to simulate a cigarette in the cigarette holder. 105

Fig. 4, is a longitudinal section through the device of Fig. 3.

Fig. 5, is a side elevation of another form of the invention in which a cigarette holder 110

is simulated and is filled with a porous material through which the liquid deodorant is fed by capillary attraction.

Fig. 6, is a longitudinal section through the form of the invention of Fig. 5, showing the construction and arrangement of the porous material.

Fig. 7, is another form of the invention in which the deodorizer simulates a cigarette.

Fig. 8, is a longitudinal section through the form of Fig. 7.

Fig. 9, is a longitudinal section through a deodorizer in the form of a cigarette, in which the deodorant feeding member is formed of fibrous material such as bamboo.

Fig. 10, is a vertical longitudinal section through a deodorizer of the invention in the form of a smoker's pipe.

Fig. 11, is a side elevation of a form of the invention designed to simulate a cigar.

Fig. 12, is a vertical longitudinal section through a modified form and construction of the invention, in which the liquid deodorant is supplied in an ampule or frangible capsule for insertion in the deodorizer and fracture thereby to supply the deodorant thereto.

Fig. 13, is a section taken on the line 13—13 of Fig. 12.

Fig. 14, is a side elevation of a deodorizer of the invention in the form of a flower.

Fig. 15, is a vertical longitudinal section through the form of the invention of Fig. 14.

According to the principles of the invention a breath deodorizer is provided in the form of a toilet novelty or accessory which is so designed as to simulate some generally carried and used article which is inserted in or touched by the mouth or can be so employed as a natural and plausible action, to supply a small quantity of deodorant to the mouth sufficient to eliminate or remove bad or objectionable breath odors. As smoking articles are in general use by both men and women and can be held in or touched to the mouth as a natural act in their use, in the preferred forms of the invention such articles are simulated, although it will be evident that the application of the invention and its various features is general and can take any other desired form in imitation or simulation of various articles, or even in such form as not to hide or cover the identity and purpose of the same.

Referring now to Figs. 1 and 2 of the accompanying drawings, a breath deodorizer of the invention is disclosed in the form and in simulation of a cigarette holder or tube. A tube or stem 10 is provided having the usual mouthpiece 11 at one end thereof and the opposite end flared or enlarged in simulation of the cigarette receiving end of such an article. The tube or stem 10 at the enlarged end thereof opposite the mouthpiece 11, is formed with an axial bore extending a

distance thereinto to form an internally threaded socket 12 at the outer portion and a chamber or reservoir 14 at its inner portion, as will be clear by reference to Fig. 2 of the drawings. A feed duct 15 extends axially through the stem 10 from the inner end of the chamber or reservoir 14 to and discharges or opens at and through the end of the stem and mouthpiece 11. A plug 16 is externally threaded for screwing into the end socket 12 of stem 10 to close the same and is provided with a cap or head 17 at the outer end thereof. A rubber or similar material washer 18 is interposed between cap 17 and the end of stem 10, around plug 16, so that the plug can be screwed tightly into and completely closing socket 12, with the washer compressed between the plug cap 17 and the end of stem 10. It will be noted that plug 16 and cap 17 are imperforate and are not formed with any vent opening from socket 12 and chamber 14, so that the socket and chamber are completely closed at their outer ends by the plug and cap.

Within the chamber or reservoir 14, a filler of absorbent, fibrous or equivalent material such as raw cotton, 19, is placed substantially filling this chamber and extending at the outer end for engagement by the inner end of the plug 16, although not so limited. A feeding member 20, in the form of a wick or such like of fibrous or porous material, is mounted in and extending through the duct 15 of the stem from and with its inner end in engagement with filler 19, to and terminating at the end of the stem in the mouthpiece 11. The reservoir or chamber 14 with the absorbent filler 19 is supplied with a suitable liquid deodorant, such as an aromatic oil, by removing plug 16 and pouring the same through the open end of the tube into chamber 14 until the filler 19 and chamber are charged therewith. The plug 16 is then inserted and the end of the tube tightly closed and sealed. The liquid deodorant will then be fed from the reservoir 14 to the mouthpiece 11 of the stem 10 by the feeding member or wick 20, through the action of capillary attraction, the member 20 becoming saturated and supplying the deodorant to the mouthpiece 11 where it can be removed by touching the tongue or lips, to the mouth. Due to feeding of the deodorant by capillary attraction to the mouthpiece, no sufficient quantity will flow to cause objectionable discharge in any position of the stem 10, but there will always be sufficient saturation of the wick 20 to supply the desired quantity to the mouth to deodorize the breath as will be readily apparent and understood.

In operation and use, the form of the invention of Figs. 1 and 2, designed in imitation of a cigarette holder is carried on the person and in public can be held in the hand

and from time to time inserted in or touched to the mouth in a natural manner as the usual custom with a cigarette holder, particularly with women, and the deodorant fed to the mouthpiece 11 will permeate or enter the mouth and deodorize the breath, without calling attention to the user as having performed any act other than to toy with a cigarette holder in a natural way customary with smokers. The reservoir 14 and absorbent filler 19 therefore will hold a sufficient quantity of deodorant to last over a considerable period of time without refilling, particularly as deodorants of a strong, 15 more or less concentrated character are preferably used, so that a minute quantity only need be taken from the mouthpiece to secure the desired results. Where the filler 19 is engaged by the inner end of plug 16, the deodorant can in effect be partially forced from the filler to the feeding member 20 by 20 tightening the plug to press upon the filler, so that as the deodorant supply approaches depletion the filler can be slightly compressed to force deodorant therefrom.

In Figs. 3 and 4 of the drawings, a deodorizer in the form of a cigarette holder similar in type to that of Fig. 1, is shown, but with the addition of an imitation cigarette 17', screw threaded at one end to form the plug 16 for closing the reservoir 14, as hereinbefore explained. Thus, with the form of Fig. 3, a more natural appearance is given the deodorizer, in that a cigarette holder with a cigarette therein is simulated and the user will convey the impression to observers that a cigarette is being smoked during the actions of deodorizing the breath. In the form of Figs. 3 and 4, a different type 40 of capillary feeding member 20' is mounted extending through stem duct 15, and comprises a rod or length of some porous or fibrous material, such as bamboo or the like.

A further modification of the invention is presented in Figs. 5 and 6 in which a deodorizer of the tube or cigarette holder type is provided and comprises the tube or shell 10 filled with and covering a porous material body 10' which at the mouth end of tube 10 extends therebeyond and is enlarged to form the mouthpiece 11. The reservoir 14 is formed in body 10' and is closed by the plug 16, as hereinbefore described. Thus, the deodorant is fed by capillary action directly through the porous body 10' to and saturates the exterior mouthpiece forming portion 11 of the body, so that contact by the mouth will supply a small quantity of the deodorant thereto.

A deodorizer forming a toilet novelty in accordance with the invention, is presented in Figs. 7, 8, and 9, in simulation of a cigarette which can be held or inserted in the mouth to give the appearance of smoking a cigarette without a holder. A tube

or cylindrical body 10 is provided having the duct 15 therethrough with reservoir 14 in communication therewith and the closure plug 16 and washer 18, a filler 19 and feeding member 20 being provided in accordance 70 with the invention. The tube 10 simulates a cigarette and the head 17" of plug 16 is designed to give the appearance of the burning or glowing end of a cigarette the opposite end of tube 10 providing the mouthpiece 75 11. In Fig. 9, the tube 10" is formed hollow and partially filled and closed by the body member 10", of a length to leave one end unobstructed to form the reservoir 14', the tube at this end being internally threaded to receive closure plug 16 with head 17".

In Fig. 10 a deodorizer is disclosed in the form and in imitation of a smoker's pipe having the stem 10, mouthpiece 11 at one end, and the bowl 21 at the opposite end 85 which forms the deodorant reservoir 14 in communication with duct 15 through the stem 10, in which the feeding member or wick 20 is disposed. The filler 19 is placed in the bowl reservoir 14, and the end of bowl 90 and reservoir are closed by the plug 16' having cap 22 which seats on washer 18 on the upper edge of the bowl. The use and operation of this smoker's pipe form of the invention is similar to that explained with regard to the preceding forms above described.

A deodorizer in simulation of a cigar is illustrated by Fig. 11 and includes the mouthpiece 11 at one end to which the deodorant is fed as explained, and the reservoir plug cap or head 17" at the other end to imitate the glowing or burning end of the cigar.

Illustrative of other forms which the invention may take in simulation of articles carried upon the person, a deodorizer in the form of an imitation or artificial flower is disclosed in Figs. 14 and 15 of the accompanying drawings, and includes the stem 10 having the axial duct 15 therethrough with 105 a feeding member or wick 20 therein. One end of stem 10 provides the discharge end of the deodorizer for application to the mouth, and the other end of the stem is bent laterally to terminate in the bowl 21' forming therewithin the deodorant chamber or reservoir 14 in communication at its inner end with duct 15 and member 20. The reservoir 14 contains the absorbent filler 19 for the deodorant, as already referred to hereinbefore. The bowl 21' is provided with the leaves or petals 23 extending radially therefrom and surrounding the same, while the bowl is closed by the plug 16' having the cap 22' which forms the center or "eye" of the flower, in cooperation with the petals 23. The form of Figs. 14 and 15, provides an artificial flower which can be inserted in the button hole or other part of the clothing, or can be carried in the hand or on other parts 115 120 125 130

of the person. By placing the end 11 of the stem to the mouth the deodorant in wick or feeding member 20 will be supplied to deodorize the breath, while the act of placing 5 the stem of a flower to or in the mouth is a natural one and will so appear to an observer.

In a modified construction embodying the principles of the invention, as shown by Figs. 10 12 and 13 of the drawings, a deodorizer in the form of a tube or cigarette holder 10 is provided with the duct 15 having the feeding member 20 therein at one end communicating with the reservoir 14 and absorbent 15 filler 19. The outer end of reservoir 14 opens into an adjacent compartment 24 formed in tube 10, and the passage between reservoir 14 and this compartment is provided with 20 the spaced projections or ears 25 therearound providing a seat, as will be later explained. The outer end of tube 10 is hollow and opens 25 into compartment 24, being internally screw threaded to receive the plug 26 having the cap 27 for bearing against the end of tube 10, or washer 18 interposed therebetween. An ampule or capsule 28 containing the liquid deodorant is placed in compartment 24, through the end of tube 10, and is formed of 30 a readily fractured or frangible material, with its inner end seated on and resting against the projections or ears 25. The plug 26 is then screwed into tube 10 until the end thereof engages ampule or capsule 28, and upon screwing plug 26 further into the tube, 35 the ampule is fractured to release the deodorant, which flows into reservoir 14 and by capillary action, through feeding member 20 to the discharge or mouthpiece end of the tube. The use of this form of deodorizer conforms to that of the forms hereinbefore described.

Thus, by the invention a breath deodorizer is provided in the form of a toilet novelty simulating any desired article carried upon 15 the person for other purposes, which can be raised to or placed in the mouth as a natural use of the article simulated without informing or advising observers as to the actual use of the device, and which will effectively 20 supply the mouth with the required quantity of deodorant to remove or overcome objectionable breath odors. The disclosure herein of various possible forms of the invention is not by way of limitation, as clearly 25 the principles and features of the invention are capable of embodiment in a wide range of forms other than those shown. The invention is not confined to use with any particular deodorant or to use solely as a deodorizer, as it includes the use for the treatment 30 of ailments of the nose, mouth and throat by placing the desired medicaments therein. The form of Fig. 12 is adapted for the treatment with gases, such as chlorine 35 gas for colds, in which gas the ampule or

capsule is filled with the gas and passes through duct 15 for discharge to the mouth, if desired the feeding member 20 being removed.

In the appended claims the term "deodorizer" or "breath deodorizer", wherever it appears, includes the use as a medicator by employing medicaments for treating the mouth, nose or/and throat, and these terms are to be interpreted and defined in accordance with the foregoing definition and scope.

It is also evident that various changes, modifications, substitutions and variations might be resorted to without departing from the spirit and scope of my invention and hence I do not wish to limit myself to the exact and specific disclosures hereof.

Desiring to protect my invention in the broadest manner legally possible, what I claim and desire to secure by Letters Patent of the United States, is:

1. In a breath deodorizer, a mouthpiece for insertion in the mouth of the user, a deodorant reservoir, and means for feeding deodorant from the reservoir to the mouthpiece by capillary action.

2. In a breath deodorizer, a body member providing a mouthpiece at one end for insertion in the mouth of a user and formed at the opposite end with a reservoir for deodorant therewithin, a duct from the reservoir to the mouthpiece, and a member extending from the reservoir to the mouthpiece through said duct for feeding deodorant by capillary action to the mouthpiece.

3. In a breath deodorizer, a body member forming a mouthpiece at one end and provided with a reservoir therein opening through the opposite end for insertion in the mouth of a user, a removable closure for sealing the open end of the reservoir, a duct from the reservoir to the mouthpiece, and an absorbent feeding member extending from the reservoir through the duct to the mouthpiece for supplying deodorant thereto by capillary attraction.

4. As a new article of manufacture, a breath deodorizer providing a toilet novelty for carrying on the person, embodying a body member in simulation of an article intended for insertion in the mouth, said body member formed with a mouthpiece and provided with means for feeding deodorant thereto.

5. As a new article of manufacture, a breath deodorizer for carrying on the person, embodying a body member formed to simulate an article for insertion in or contact with the mouth, said member providing a mouthpiece and formed with a deodorant reservoir therewithin, and capillary means for feeding deodorant from the reservoir to the mouthpiece.

6. As a new article of manufacture, a breath deodorizer comprising a body mem-

ber formed to simulate a smoker's article provided with a mouthpiece, and capillary means within the body member for feeding deodorant to the mouthpiece.

5 7. As a new article of manufacture, a breath deodorizer comprising a body member formed to simulate a tobacco holder provided with a mouthpiece, said member formed with a deodorant reservoir opening 10 through the supposed tobacco holding end thereof, means for feeding deodorant from the reservoir to the mouthpiece, and a removable closure for the open end of the reservoir formed to simulate a tobacco article when inserted in said body member.

8. In a breath deodorizer, a body member provided with a mouthpiece at one end and formed with a deodorant reservoir adjacent to and opening through the opposite end 20 thereof, an absorbent filler for deodorant within said reservoir, means for feeding deodorant by capillary attraction from the

reservoir and filler to the mouthpiece, and a removable closure for the open end of the body member and reservoir, said closure 25 adapted to bear against and exert pressure upon said absorbent filler.

9. In a breath deodorizer, a body member provided with a mouthpiece at one end and a deodorant reservoir adjacent and 30 opening through the opposite end thereof, an absorbent filler for deodorant within the reservoir, a duct from the reservoir to the mouthpiece, an absorbent feeding member extending from the reservoir and filler, 35 through and occupying the duct for feeding deodorant by capillary action to the mouthpiece, and a removable closure for the open end of the reservoir, said closure in mounted position adapted to exert pressure upon said 40 reservoir filler to compress the same.

Signed at Washington, D. C., this 29th day of January, 1926.

WM. F. PATTEN.
